UNITED STATES PATENT OFFICE.

MAX RITTER VON PITTONI, OF BUDA-PESTH, AUSTRIA-HUNGARY.

OVEN.

SPECIFICATION forming part of Letters Patent No. 392,649, dated November 13, 1888.

Application filed November 3, 1887. Serial No. 254,233. (No model.)

To all whom it may concern:

Be it known that I, MAX RITTER VON PITTONI, of Buda-Pesth, Austria-Hungary, have invented an Improvement in Ovens, of which the following is a specification.

This invention relates to a portable kitchen of improved construction; and it consists in the various features of improvement, more fully pointed out in the claim.

10 In the accompanying drawings, Figure 1 is a vertical transverse section through my improved portable kitchen. Fig. 2 is a front view, and Fig. 3 a side view, of one of the bars supporting the frying-pans.

15 The letter A represents an oven having the side doors, G, and top plate, D'. Back of the doors G there is another pair of doors, H, that is provided with a series of horizontal slots for the introduction of the frying-pans K.

20 The frying-pans are supported upon bars F', removably secured to brackets F, which are attached to uprights J'. These uprights are fastened to the side walls of the oven.

P' are the doors for the ash-pit beneath the oven, and B' is the bottom plate of such ash-pit. 25

Z is a smoke-flue, which covers the opening M' for the fire-gas. Through the fire-chamber there extends a central wall, O, and it contains the grates R. 30

N' is one of the doors, connecting the oven with the cooking-chamber.

What I claim is—

The combination of oven A, with brackets F, removable bars F', and with uprights J', 35 slotted doors H, and outer doors, G, substantially as specified.

In testimony whereof I have signed my name to this specification in the presence of two subscribing witnesses.

MAX RITTER V. PITTONI.
